UNITED STATES PATENT OFFICE.

MARION WALLACK AND JACOB B. ROHRER, OF CAMBRIDGE CITY, INDIANA;
SAID WALLACK ASSIGNOR OF ONE-HALF HIS RIGHT TO BENJAMIN ESHELMAN, OF EAST GERMANTOWN, INDIANA.

RAILWAY-CROSSING.

SPECIFICATION forming part of Letters Patent No. 295,844, dated March 25, 1884.

Application filed November 16, 1883. (No model.)

To all whom it may concern:

Be it known that we, MARION WALLACK and JACOB B. ROHRER, of Cambridge City, in the county of Wayne and State of Indiana, have invented certain new and useful Improvements in Railway-Crossings; and we do hereby declare the following to be a full, clear, and exact description of the invention, such as will enable others skilled in the art to 10 which it appertains to make and use the same.

Our invention relates to an improvement in railway-crossings, the object being to provide means whereby the necessity of cutting the rails of the main track shall be obviated, 15 and whereby the use of all guard-rails shall be avoided; and with these ends in view our invention consists in certain details of construction and combinations of parts, as will be hereinafter described, and pointed out in the 20 claims.

In the accompanying drawings, Figure 1 is a plan view of our improved crossing, the main track being open or unobstructed. Fig. 2 is a sectional view with the siding in its unobstructed position. Fig. 3 is a detached view of the pivoted portion of the side rail. Fig. 4 is a detached view of the block or rest.

A A represent the rails of the main track, and B B the rails of the siding.

C represents the movable portion of the side rails, being secured to a block of iron, a, or other suitable material, which latter is pivoted to a tie, D, and allows the portion C to be moved in a position parallel, or nearly so, with the rails A. The pivoted portion C is raised a short distance above the rails A, the web and base of the same being cut away from the point b, where it comes in contact with rail A, the remaining tread of the rail resting 40 on the track A, and extending to the stationary rail B, the flanges of the wheels in passing over the siding by these means being prevented from coming in contact with the rails A.

E represents a block or rest, the top of 45 which is on a line with the tread of the rail A, and is adapted to support the end of the pivoted rail C when the siding is in position for travel. This block E is situated against

the rail A, and at the end of the rail B, and is provided on its upper face with a groove, 50 F, for the passage of the flanges of the car-wheels passing over the rails A, the upper face being also provided with a pivoted spring-actuated cap, G, which fits against the end of the rail B, and is provided with the downward-inclined face c, said cap being adapted to keep the upper bearing-face of the block free from obstructions, which might prevent the end of the pivoted rail C from assuming 60 its proper position in relation to the stationary rail B. When the pivoted portion C of the rail B is moved in position for travel over the siding, the end of the rail C strikes the free end of the cap G, and moves the same around, the said latter being pivotally secured 65 to the block at d, the cap assuming its normal position when the rail C is removed from contact therewith.

To the free end of the pivoted portion C is secured a bent metal plate, H, the upper portion of which is bent out to conform to the shape of the tread of the rail A, and the side of which is also bent to adapt it to the shape of the web and base of said rail A, the lower portion of the plate being bent parallel with 70 and adapted to bear on the plate I, secured to the ties. When the pivoted section C is in line with the rail B, the said plate H rests on and against the rail A, and assists in keeping said section C in proper position. To 75 the lower portion of this plate H is secured the rod or lever K, by which the device is operated.

It will now be seen that by our improved device the main rails are left solid, and the 85 necessity of guard-rails entirely avoided.

Our invention is simple and economical in construction, is of few parts, and is durable and efficient in use.

Having fully described our invention, what 90 we claim as new, and desire to secure by Letters Patent, is—

1. The combination, with the rails A A, of the rails B B, the pivoted section C, constructed as described, and the plate H, bent 95 to conform to the shape of the rail A, and

adapted to retain said pivoted section in position thereon, substantially as set forth.

2. The combination, with the rails B B, of a pivoted section connecting the ends of one of the rails B, and the block or rest E, provided with a spring-actuated cap, substantially as set forth.

In testimony whereof we have signed this

specification in the presence of two subscribing witnesses.

MARION WALLACK.
JACOB B. ROHRER.
